UNITED STATES PATENT OFFICE.

WILLIAM A. MORTON, OF LOS ANGELES, CALIFORNIA.

TURBINE.

Application filed November 12, 1925. Serial No. 68,632.

To all whom it may concern:

Be it known that I, WILLIAM A. MORTON, a citizen of the United States, residing at Los Angeles, in the county of Los Angeles and State of California, have invented new and useful Improvements in Turbines, of which the following is a specification.

My invention is a turbine, particularly adapted for use in driving tools in well boring, or as a rotary hand tool for driving various portable tools.

An object of my invention is to form a turbine which may be driven by a liquid or compressed gas, such as water, air or steam and to form a mounting for the turbine so that it may be located at the bottom of well piping or a well boring rod to utilize the turbine to drive various types of well drilling and boring tools having a rotary action.

20 A further feature of my invention is a turbine base forming a housing for the turbine, the base having a screw threaded rim in which a packing cap may be attached and the packing cap having an eduction plate 25 also forming a journal and having eduction passages for the discharged liquid or gas used in the turbine.

My invention will be more readily understood from the following description and 30 drawings, in which;

Figure 1 is a side elevation of the turbine showing the manner in which it is completely enclosed with the eduction plate illustrated by a broken section.

35 Fig. 2 is a vertical section of Fig. 1, on the line 2—2 in the direction of the arrows, showing the turbine housing, the turbine, a packing cap forming a closure for the journal housing and a journal for the turbine shaft and an eduction plate also forming a journal.

40 Fig. 3 is a horizontal section on the line 3—3 of Fig. 2, in the direction of the arrows, indicating the flow passages in the turbine housing and the turbine.

Fig. 4 is a horizontal section of Fig. 2, on the line 4—4 in the direction of the arrows.

50 Fig. 5 is an end view of the turbine rotor as if taken in the direction of the arrow 5 of Fig. 6.

Fig. 6 is a side elevation of the turbine rotor in the direction of the arrow 6 of Fig. 5.

55 Referring particularly to Figs. 1 and 2, a turbine housing 1 is preferably formed

with a standard tapered upper end 2 adapted to connect to a well boring rod 3 in the form of a pipe. The housing has a central bored passage 4 for the compressed gas or liquid being used. A diagonal passage 5 connects with the passage 4 and is closed at the outer end by a plug. A turbine chamber 7 is formed in the base of the housing for the turbine and a recess 8 for a thrust bearing as hereafter described. An inlet duct 9 leads from the passage 5 to the turbine chamber 7 and an outlet duct 10 is formed on the opposite side of the housing from the duct 9 for the waste fluids.

A rim 11 on the lower edge of the housing is internally screw threaded and receives a packing cap 12, this having a reduced upper end 13 having a screw threaded engagement with the rim 11. This packing cap has an internal socket 14 and an annular deep groove 15 with a discharge duct 16 leading from the outlet duct to the annular groove 15.

50 A skirt 17 depends from the packing cap and has an internally screw threaded portion 18 in which is fitted a screw threaded eduction plate 19. This plate has two eduction ports 20 inclined at an angle. It is to be understood that there may be any suitable number of such ports to freely carry away the fluid used by the turbine.

The turbine rotor is illustrated particularly in Figs. 2, 3 and 5 and is designated generally by the numeral 21, having a hub 22 with vanes 23 extending somewhat radially outwardly from the hub, these vanes however being properly curved to catch the fluid for operating the turbine and to properly discharge said fluid.

55 It will be noted that the inlet port 24 from the inlet duct 9 to the turbine chamber 7 is at an inclination in the direction of rotation as indicated by the arrow in Fig. 3 and the outlet port 25 also has inclined walls from the turbine chamber 7 to the outlet duct 10. The turbine rotor is keyed to a shaft 26 which may be designated as the turbine shaft.

60 The manner of journaling the turbine shaft is substantially as follows, being indicated in Fig. 2.

A cup 27 is screw threaded into the recess 8 above the turbine chamber and a block 28 fits therein. On this block is placed a flat ring 29, the latter supporting an internal ball race 30. An external ball race

31, there being balls 32 between the races, bears against the inner portion of the recess 8 and against the flat inner end 33. The shaft 26 has a shoulder 34 engaging the inner ball race 30 and the upper end of the shaft may be slightly coned as indicated at 35, extending into the coned socket 36, this however, is merely a clearance space to allow play of the shaft. The above construction forms a thrust bearing for the shaft as well as forming a centering bearing to maintain the turbine in proper alignment.

15 A shaft journal 37 is formed of the inner and outer ball races 38 and 39 with balls 40 therebetween, these being situated in a journal socket 41 in the eduction plate 19, this forming a bearing for the lower portion of the shaft maintaining it in proper alignment.

20 A packing of any suitable character 42 is inserted in the internal socket 14 of the packing cap 12 and packing 43 is inserted in a socket 44 formed by a collar 45 projecting downwardly from the eduction plate 19. This packing is held in place by a flat ring 45 and an expanding spring 46.

25 The lower end 47 of the turbine shaft may be of any suitable shape and adapted to be connected with various tools. In well drilling operations these may be well boring tools of a rotary type, or if used for surface operations various suitable rotary tools.

30 It is believed that the manner of operation of my turbine is clear, however, it may be stated that a fluid such as compressed air will be forced down the pipe 3 through the passages 4 and 5, the inlet duct 9, inlet bore 24 and actuate the turbine by impinging on the vanes 23. The outlet port 25 leads to the outlet duct 10 and the compressed air is educted from the turbine by passage through the discharge duct 16, the annular groove 15 and the eduction ports 20 in the eduction plate 19.

35 It will thus be seen that the turbine is completely enclosed and protected from the drains of any dirt or in oil or water wells from the oil or water, the gas or liquid being exhausted, keeping materials detrimental to the action of the turbine from passing to the eduction plate 19.

40 It will be readily understood that in well boring the turbine housing could be maintained sufficiently rigid to prevent it from rotation and thus a high speed boring or drilling action may be obtained. If my turbine is to be utilized for surface work, for attaching tools thereto or form the driving power for a pulley or the like, a supply pipe for gas or liquids will be attached to the internally screw threaded end 50 of the passage 4, the turbine housing being of such size as to be readily grasped in the hand or held in a suitable supporting bracket.

45 It is manifest that my general turbine

construction may be considerably modified to suit different types of work for which it may be designed, such changes embodying the general features and specific details and these modifications will be within the spirit 70 of my invention as set forth in the description, drawings and claims.

Having described my invention, what I claim is:

1. A turbine comprising in combination 75 a turbine housing having a turbine chamber in one end, a packing cap secured to the end of the turbine housing, a turbine rotor having a shaft mounted in the turbine chamber, a thrust bearing for the turbine shaft, mounted in a recess in the turbine housing, adjacent the turbine chamber, and inlet passages through the turbine housing to the turbine chamber, and outlet passages through the turbine housing and the packing 80 cap from the turbine chamber.

2. A turbine as claimed in claim 1, having in addition an eduction plate attached to the packing cap, said eduction plate having 85 ports therethrough.

90 3. A turbine comprising in combination a turbine housing having a turbine chamber at one end, a packing cap attached to the end of the turbine housing, forming a closure for the said chamber, an eduction plate secured to the packing cap, a turbine rotor having a shaft mounted in the turbine chamber, and inlet passages for fluid through the turbine housing to the turbine chamber and from the turbine chamber through the packing 95 cap and the eduction plate.

100 4. A turbine as claimed in claim 3, in which the packing cap has deep grooves conducting the fluid between the passage through the packing cap to the passages 105 through the eduction plate.

110 5. A turbine as claimed in claim 3, having in addition a thrust bearing for the turbine shaft in the turbine housing and a side bearing for the shaft in the eduction plate.

115 6. A turbine comprising in combination a cylindrical turbine housing having an open end with a turbine chamber formed therein, and a recess for bearings inwardly of the turbine chamber, a packing cap screw threaded on the end of the turbine housing forming a closure for the turbine chamber, inlet passages in the turbine housing leading from one end, an inlet duct having an inlet port at one side of the turbine chamber, an outlet port and outlet duct at the other side of the turbine chamber, a discharge duct through the packing cap, a turbine rotor mounted in the turbine chamber having a shaft, said shaft having a thrust bearing in the said recess and passing through the packing cap.

120 7. A turbine as claimed in claim 6, having in addition an eduction plate screw thread-

ed on the packing cap, having eduction ports therethrough, and the said packing cap having a deep annular groove forming a passage for the fluid from the said discharge duct to the said eduction ports.

8. A turbine comprising in combination a cylindrical turbine housing having a cylindrical turbine chamber at one end, a recess for bearings inwardly of the turbine chamber, a rim extending downwardly from the turbine housing, a packing cap screw threaded to the said rim, the packing cap having a depending skirt, a portion of which is internally screw threaded, an eduction plate threaded to the threaded portion of the packing cap, the said packing cap having a deep annular groove adjacent the side of the eduction plate, a turbine rotor mounted in the turbine chamber, a shaft having a thrust bearing in the said recess, the said shaft extending through the packing cap and the eduction plate, and passages through the turbine housing to the turbine chamber and

from the turbine housing through the packing cap and the eduction plate.

9. A turbine as claimed in claim 8, in which the passages for fluid include a central passage in the turbine housing at the opposite end from the turbine chamber, an inclined passage connected therewith, an inlet duct at one side of the turbine chamber, an outlet duct on the opposite side of the turbine chamber, a discharge duct in the packing cap connecting with the outlet duct and eduction ports through the eduction plate.

10. A turbine as claimed in claim 8, in which the thrust bearing in the said recess is of an anti-friction type and a lateral bearing of the anti-friction type in the eduction plate with packings in the packing cap and in the eduction plate for the shaft.

In testimony whereof I have signed my name to this specification.

WILLIAM A. MORTON.
